United States Patent Office.

HENRY DISSTON, OF PHILADELPHIA, PENNSYLVANIA.

Letters Patent No. 79,213, dated June 23, 1868.

IMPROVEMENT IN DEVICE FOR HOLDING ROTARY CUTTERS WHILE BEING GROUNDED.

The Schedule referred to in these Letters Patent and making part of the same.

TO ALL WHOM IT MAY CONCERN:

Be it known that I, HENRY DISSTON, of Philadelphia, Pennsylvania, have invented an Improvement in Instruments for Holding Rotary Cutters while being Ground; and I do hereby declare the following to be a full, clear, and exact description of the same.

My invention relates to an improvement on the "cutter-grinder," for which Letters Patent of the United States were granted to N. F. Stone, on the seventeenth day of April, 1866, and my improvement consists of certain devices, fully described hereafter, for holding and adjusting the cutter while it is applied to a grindstone, so that the teeth shall all be reduced to a uniform size and shape, and the truth of the cutter preserved.

In order to enable others skilled in the art to make and use my invention, I will now proceed to describe its construction and operation, reference being had to the accompanying drawing which forms a part of this specification, and in which—

Figure 1 is a sectional view of my improved instrument for holding rotary cutters while being ground, and Figure 2 an inverted plan view.

From one end of an oblong metal frame, A, projects a handle, *a*, and at the opposite end is an adjustable slide, B, which is secured to the frame by a set-screw, *b*, and carries at its lower end a roller, *c*.

On the under side of the frame, near its rear end, are lugs, through which extends a pin, *e*, and on the latter turn rollers, *ff*, the openings in the lugs being elongated, so that the said pin, with its rollers, may be adjusted vertically, set-screws, *t*, serving to secure the pin after adjustment.

In lugs *g*, on the lower side of the frame, near the centre of the same, are recesses or bearings for the reception of the spindle X of a rotary cutter, Y, the latter, in the present instance, being similar to those employed in saw-gumming machines.

A set-screw, *n*, passes through a slot in an elastic plate, *h*, and secures the latter to the rear end of the frame, and at the lower end of the plate is a lip, *i*, for a purpose described hereafter.

The shaft of the cutter to be sharpened is introduced into the recesses or bearings in the lugs *g*. The lip *i* of the elastic plate *h* is made to catch against one of the teeth of the cutter, and the plate is adjusted and secured in such a position that on the instrument being applied to the grindstone the outer edge of the lowermost tooth of the cutter will be brought against the edge of the stone.

After the first tooth has been ground to the required extent, the slide B is depressed until the roller *c* is in contact with the edge of the stone. The spindle X is now turned in the direction of its arrow, the end of the plate *h* being forced back by the inclined side of the tooth against which it bears, until the straight edge of the tooth is brought in contact with the lip *i*, when another tooth will be in a position to be ground on the application of the instrument to the stone as before.

It will be evident that the bevel imparted to the edge of the tooth will depend upon the extent to which the cutter is turned before applying the tooth to the stone, the position of the cutter in this respect being regulated by adjusting the plate *h*, while the length of the tooth will be determined by the position of the rollers, so that after the adjustment of the plate and rollers all the teeth may be ground to precisely the same size and bevel without its being necessary for the operator to exercise any further care than is required to apply the instrument to the stone, and to turn the cutter as its teeth are successively ground.

It is advisable that the rollers *ff*, as well as the rollers *cc*, should be adjustable vertically from time to time, otherwise, as the cutter is reduced by grinding, the proper bevel will not be imparted to the ends of the teeth.

I claim as my invention, and desire to secure by Letters Patent, as an improvement on the aforesaid invention of N. F. Stone—

The frame A, arranged for the reception of the spindle of a rotary cutter, as set forth, in combination with the rear rollers *f*, and the vertically-adjustable roller *c*, substantially as and for the purpose specified.

In testimony whereof, I have signed my name to this specification in the presence of two subscribing witnesses.

HENRY DISSTON.
